CLAIM

The ornamental design for a bathroom tissue roll dispenser, as shown.

DESCRIPTION

FIG. 1 is a front elevational view of a bathroom tissue role dispenser showing our new design;

FIG. 2 is a left side elevational view thereof.

FIG. 3 is a fragmentary right side elevational view thereof, the broken line showing of the screws and the wall being for illustrative purposes only;

FIG. 4 is a top plan view thereof.

FIG. 5 is a bottom plan view thereof.
